(57) **CLAIM**

The ornamental design for a motor switch lever, as shown and described.

DESCRIPTION

FIG. 1 is a perspective view of a motor switch lever showing our new design;

FIG. 2 is another perspective view thereof, opposite that of FIG. 1;

FIG. 3 is another perspective view thereof, taken from a different angle than FIG. 1;

FIG. 4 is a front elevation thereof;

FIG. 5 is a rear elevation view thereof;

FIG. 6 is a top plan view thereof;

FIG. 7 is a bottom plan view thereof;

FIG. 8 is a side elevation view thereof; and,

FIG. 9 is another side elevation view thereof, opposite that of FIG. 8.

The broken lines shown represent unclaimed subject matter and form no part of the claim. Where broken lines abut a claimed surface it is understood that those broken lines represent an unclaimed boundary between claimed and unclaimed surfaces. None of the broken lines form any part of the claimed design.
